BINGO BOARD WITH PIVOTED SHUTTER

Earl P. Buchmiller, Denver, Colo.

Application January 29, 1951, Serial No. 208,341

1. Claim. (Cl. 273—135)

1

This invention relates to number-bearing cards or boards of the general type, form and style commonly utilized in play of the game bingo, a currently-popular variant of lotto or of the derivatives of the latter known as keno and beano, and has as an object to provide an improved such card or board well and particularly adapted for repetitious use in such play.

A further object of the invention is to provide an improved construction and relationship of elements constituting a bingo board adapted for convenient, repetitious use in game play.

A further object of the invention is to provide an improved bingo board characterized by visually-exposed numbers and associated means selectively manipulable into individual covering relation with such numbers.

A further object of the invention is to provide an improved number-bearing bingo board characterized by means operatively board-mounted in association with each of the numbers for selective manipulation between covering and uncovering relation with the associated number.

A further object of the invention is to provide an improved number-bearing bingo board characterized by means operatively board-mounted in association with each of the numbers for selective manipulation between covering and uncovering relation with the associated number and for simultaneous shift to a common limit of their adjustable range in reaction to board-applied influences.

A further object of the invention is to provide an improved bingo board that is simple and inexpensive of production, complete and self-contained for play purposes, convenient of use, positively indicative of appropriate play registrations, smooth, flat and compact in form, and susceptible of repetitious play use throughout a period determined only by the durability of the materials of its construction.

With the foregoing and other objects in view, my invention consists in the construction, arrangement, and combination of elements as hereinafter set forth, pointed out in my claim, and illustrated by the accompanying drawing, in which—

Figure 1 is a plan view of the playing face of a typical bingo board embodying the principles and improvements of the instant invention. Figure 2 is a cross section, on an enlarged scale, taken substantially on the indicated line 2—2 of Figure 1. Figure 3 is a detail, isometric view of a shutter element employed in multiple in the constitution of the board as shown in the preceding views. Figure 4 is a view similar to Fig-

ure 3 illustrating a modified form of shutter element. Figure 5 is a fragmentary, detail elevation, on an enlarged scale, of the upper left-hand area of Figure 1, a portion of the showing being broken away to disclose otherwise concealed relationships. Figure 6 is a fragmentary, detail section, on an enlarged scale, taken substantially on the indicated line 6—6 of Figure 1. Figure 7 is a section similar to Figure 6 illustrating use of the shutter element according to Figure 4.

As is well known, play of the game bingo, or of the similar games lotto, keno and beano, involves the use of certain facilities, one of which is a card or board bearing and visually exhibiting numbers in any convenient rectangular pattern effective to dispose five play numbers in each of several transverse or horizontal rows. At the start of play, all of the numbers on the play field of the card or board are clearly exposed, and as the play progresses, board or card numbers corresponding with numbers selected by hazard are covered, or otherwise clearly distinguished, until a proper sequence of covered numbers, usually all five numbers characterizing any one transverse or horizontal row, on any board or card in play, determines the winner. Manifestly, the cards or boards are adapted for repetitious use in the playing of successive games, when appropriate provision is made for designating the called numbers without marking or disfiguring the card, and to that end it is conventional to use individual markers, separate from the card or board, to cover or mark on the individual play fields the called numbers that appear thereon, but such individual, separate markers are susceptible of loss, inconvenient of use, and easily displaced relative to a card or board whereon they have been positioned, hence the instant invention is directed to the provision of a board or card unit for use in play of the games set forth that is susceptible of repetitious use with none of the disadvantages of hitherto conventional such units.

As illustrated, the improved board is constituted from two coextensive like or similar sheets or cards 10 and 11 superposed in marginal registration and permanently united by appropriate means, such as stitching, stapling, adhesive agents, or an adhesively-secured tape binding 12, extending along and entirely about the registered margins of the elements 10 and 11. The sheets or cards 10 and 11 may be of any suitable material characterized by the properties of stiffness, strength, and durability appropriate to the intended use, considerations of availability and economy favoring paperboard as eminently

practical for the production of such elements in quantity. One of the sheets or cards, in this instance the element 10, forms the back of the unit assembly, is imperforate, and is imprinted or otherwise worked on its face adjacent and largely covered by the element 11 to exhibit a jumbled series of numbers 13 in an order and pattern suitable for game play, and the sheet or card element 11 is intersected by a plurality of like windows or openings 14, preferably rectangular, corresponding in number and arrangement with the individual number 13 representations on the associated element 10 so as to visually expose said numbers 13, individually, through said windows to present an obverse play face of the unit assembly closely simulating the play face of conventional bingo cards or boards. In addition to the patterned arrangement of play numbers 13, each of the card or board units customarily carries an identification number or symbol which, in the improved construction, may be marked or imprinted on the face of the element 10 carrying the numbers 13, as at 15, in position for exposure through an appropriate window 16 intersecting the element 11 in offset relation with the window 14 pattern.

As is readily apparent, the card or board constituted as thus far described is the functional equivalent of conventional bingo cards or boards and is available for use in game play in association with separate markers or analogous means for covering or distinguishing those of the numbers 13 that have been called in play, but a significant feature of the improvement is the provision of a shutter or marker permanently associated with each number 13 and its window 14 in a manner facilitating adjustment of the shutter to either cover or expose the associated number, as illustrated and hereinafter described.

As shown in Figures 1, 2, 3, 5, and 6, the shutter or marker characterizing the improvement is a thin, flat member 17 of suitable sheet material receivable between the adjacent, interior faces of the elements 10 and 11, it being feasible and desirable, though not essential, to form said members 17 from transparent sheet plastic in a color contrasting with that of the element 10 and 11 exposed areas. The members 17 of each unit assembly are alike, one such member being supplied for each of the play numbers 13 of the unit, and each said member 17 is conveniently of modified rectangular form to present, in plan, a major end area slightly greater than the open area of the number-exposing window 14 and a reduced, opposite end area outlined between a colinear extension of one of the major area side margins and an edge inwardly inclined from the other major area side margin to mergence with said colinear extension in a manner definitive of a tapered finger portion 18. A cylindrical stud 19 is fixed to outstand from the reduced end of the finger portion 18 with its axis perpendicular to the plane of the member 17 in a length not exceeding the thickness of the element 10 and said stud is received in a hole 20 formed for its accommodation through the element 10 in such relation with each of the windows 14 as will pivotally position a member 17 major end area to underlie the window in covering relation with the number 13 exposable therethrough and, alternatively, to clear the associated window for full and clear exposure of said number, to which end each of the members 17 is engaged by means of its stud 19 in a hole 20 appropriately correlated with the position of each of the numbers 13 and

the associated exposure window 14. For selective manipulation of the individual shutters relative to their respective windows 14 and for limiting the range of individual shutter oscillation about the pivotal mounting thereof, a pin 21, the same as or similar to the stud 19, is fixed to outstand perpendicularly from the face of each shutter member 17 opposite to that carrying the said stud and is disposed inwardly adjacent the member straight side margin common to the major area and finger portions of the member in such spaced relation with the stud 19 as will serve to accommodate the said pin in a window 14 of the element 11 when the stud of the same shutter member is engaged in the hole 20 of the element 10 appropriate to mount the shutter in selective covering relation with the number 13 exposable through said window. The pin 21 preferably has a length perpendicular to its member 17 approximately equaling the thickness of the element 11 and less than will interfere with stacking of the unit board assemblies in superposed relation, in which length proportion said pin is presented through its window 14 for convenient engagement by the finger of an operator and for consequent manipulation effective to shift the associated shutter on its pivotal mounting between covering and exposing relations with the window-exposed number 13. As is manifest, engagement of the pin 21 with the opposite sides of its accommodating window 14 operates to limit oscillatory range of the associated shutter, and the location of the pin on its shutter member 17 is such as to establish a limit of shutter oscillation in one direction such as will dispose the shutter major area to fully underlie the window 14 in full covering relation with the number 13 exposable therethrough and to establish a limit of shutter oscillation in the other direction such as will clear the shutter major area from obstructing relation with the window, save for a small triangular zone at the pin base, in a manner to fully expose the said number through the window. Hence, in the arrangement shown and described, the shutters may be individually and selectively manipulated to cover and thereby clearly designate any and all of the numbers 13 exposable through the windows 14 of a given board unit, shutter members 17 of opaque material functioning to completely blank the covered numbers from view and such members when made of transparent material of contrasting color functioning to clearly distinguish the covered numbers while permitting exposure thereof. The shutters are adequately retained in any position of their adjustment relative to their associated numbers and windows by virtue of the frictions developed between the member 17 faces and the element 10 and 11 areas in contact therewith, it being expedient to proportion the spacing between said elements 10 and 11, by means of marginal spacers 22, if desired, to the thickness of the shutters to assure clamping of the shutters under appropriate retentive pressure. While the shutters are primarily designed and arranged for individual adjustment as an incident of game play, the construction shown and described accommodates simultaneous adjustment of all the shutters of a board unit to a like limit of their shiftable range, since, with the board unit held in a vertical plane, a tap of one of the board unit upper corners against the hand or other object operates to shift all of the shutters in the same direction and to the limit of their adjustability adjacent the struck hand or object, there-

by clearing the board unit for full exposure of all of its numbers 13 or, conversely, interposing a shutter area between each of said numbers and its exposure window, as one or the other of the board upper corners is struck.

The modified construction according to Figures 4 and 7 is in all functional and operative respects identical with that shown in the other views and hereinabove described, the only peculiarities of the modified construction being a reversal of the stud 19 position and a corresponding change in the location of the hole 20 wherein said stud engages. As shown in Figure 4, the stud 19 may be fixed to the shutter tapered finger portion 18 to outstand perpendicularly from the same side of the member 17 as the pin 21, in which event the hole 20 for pivotal accommodation of each stud 19 is formed in and through the board element 11, rather than in and through the element 10, and the assembly is completed for use and operation exactly as first described; location of the holes 20 in the element 11 which carries the windows 14 and 16 facilitating production through a concentration of all punching operations on a single element of each unit assembly.

While adapted for production from various materials and through the application of various techniques, the shutter units comprised in the improvement are susceptible of being conveniently and advantageously molded from so-called "plastic" material in either of the forms shown and described.

Since changes, variations, and modifications in the form, construction, and arrangement of the elements shown and described may be had without departing from the spirit of my invention, I wish to be understood as being limited solely by the scope of the appended claim, rather than by any details of the illustrative showing and foregoing description.

I claim as my invention:

In a bingo board wherein a patterned arrangement of play indicia on one face of a card is exposed to view through rectangular window openings intersecting a second card closely and

loosely overlying the patterned face of said first card in coextensive, marginally-engaged relation with said first card, shutter means selectively manipulable into and out of obstructing relation with each said window opening and comprising a thin, flat member slidably engaged between said first and second cards in association with each window opening, a major end area on the member slightly greater than the associated window opening, a finger portion extending and tapered to a narrow free end from said major end area in alignment of one of its sides with the correspondingly positioned major end area side, a cylindrical stud perpendicularly outstanding from the finger portion free end, a hole for the accommodation of said stud intersecting one of said cards spacedly adjacent the associated window opening and in substantial alignment with a side margin thereof, whereby to pivotally engage the member with one of said cards for oscillation into and out of obstructing relation with the window opening, and a pin outstanding from the member major end area adjacent the side thereof coaligned with the finger portion and in spaced parallelism with said stud disposed for accommodation within the outline of the associated window opening when the stud is pivotally engaged with the card, whereby to constitute said pin as a means for manipulation of said member and as a stop engageable with opposite margins of the window opening to limit swing of the member major end area relative to the said opening.

EARL P. BUCHMILLER.
